US0D1092552S

(12) **United States Design Patent** (10) Patent No.: **US D1,092,552 S**
(45) Date of Patent: ** Sep. 9, 2025

(54) **DISPLAY SCREEN WITH ICON**

(71) Applicant: **CENTRALSCALE TECHNOLOGIES, LLC**, Lake Mary, FL (US)

(72) Inventors: **Ye Zhou**, Oviedo, FL (US); **Ryan Trenholm**, Kelowna (CA); **Jason Parker**, Clarkesville, GA (US); **Emily Dalton**, Harrisonburg, VA (US)

(73) Assignee: **CENTRALSCALE TECHNOLOGIES, LLC**, Lake Mary, FL (US)

(**) Term: **15 Years**

(21) Appl. No.: **29/960,328**

(22) Filed: **Aug. 29, 2024**

Related U.S. Application Data

(63) Continuation of application No. 29/868,216, filed on Nov. 25, 2022, now Pat. No. Des. 1,045,928.

(51) **LOC (15) Cl.** **14-04**

CLAIM

The ornamental design for a display screen with icon, as shown and described.

DESCRIPTION

The FIGURE is a front view of a display screen with an icon, showing our new design.

The broken lines of uneven length show the display screen and form no part of the claimed design.

1 Claim, 1 Drawing Sheet
